W. E. BROWN

FOLDING COT

Filed Sept. 10, 1925

INVENTOR.
William E. Brown.

BY
R. W. Sint.

ATTORNEY.

UNITED STATES PATENT OFFICE.

WILLIAM E. BROWN, OF LOS ANGELES, CALIFORNIA.

FOLDING COT.

Application filed September 10, 1925. Serial No. 55,433.

It is the object of this invention to provide a cot which may be readily folded or extended for use; and which is constructed without the use of side rails in order to provide a comfortable structure which is relatively light and adapted for folding into compact form.

It is a further object of the invention to provide an extremely simplified construction, which when extended for use is positively braced in all directions so as to form a rigid structure adapted to support an appreciable weight without danger of collapse.

It is a still further object of the invention to provide means for quickly adjusting the tension of the supporting canvas of the cot so as to adapt the same to individual requirements.

Further objects of the invention will be readily understood from the following description of the accompanying drawings, in which:

Fig. 1 is a perspective view of the cot in position for use.

Fig. 2 is an end elevation of the cot partly in vertical section.

Fig. 3 is a side elevation showing the method of folding the cot.

Fig. 4 is a perspective view of the folded cot.

Fig. 5 is a detail section on the line 5—5 of Fig. 1.

Fig. 6 is a detail section through the releasable connection for a brace of the cot.

The cot is mounted upon a base bar which consists of elongated members 1 of relatively narrow width and provided with a hinge connection 2 at the underside of their abutting ends 3, so that when the cot is in use the base bar will rest upon the ground with members 1 in longitudinal alinement and held against relative swinging by the abutment of their hinged ends.

End frames are mounted upon members 1 and each preferably includes top and bottom rails 4 and 5 connected at their ends by uprights 6. Pivotal connections 7 are provided between the uprights and the top and bottom rails, so that the end frames may assume a rectangular position as shown in Fig. 2, or the uprights may be swung downwardly as shown in dotted lines in Fig. 2 to collapse the top rail upon the bottom rail as shown in Fig. 3.

In order to rigidly secure the end frames in rectangular position adapted for use, the

corners of the frames are braced by members 8 pivoted to the uprights as shown at 7, and adapted to releasably engage the top rails 4. The releasable connections preferably include hooks 9 at the ends of the braces received over projecting studs 10 on the top rails, the ends of the studs being threaded to receive clamping nuts 11, so that tightening of the nuts will prevent disengagement of hooks 9, while releasing of said clamping engagement will permit disengagement of the braces for swinging the end frames to collapsed position.

When the cot is extended for use the rectangular end frames extend transversely of the base bar, with bottom rails 5 connected to members 1 and the sides of the end frames resting upon the ground by means of legs 12, forming prolongations of uprights 6. The end frames are adapted to swing relative to the base bar upon the axes of bottom rails 5, and for this purpose the connections between the bottom rails and members 1 comprise bearings 13 having the bottom rails journaled therein midway of their lengths so that the end frames will project equidistantly beyond the sides of the base bar.

Bearings 13 are pivotally mounted upon members 1 as shown at 14, so that when the cot is folded, the end frames may be first collapsed and then turned parallel to the members 1 as shown in Fig. 3.

The supporting surface of the cot is preferably a canvas 15 which is connected at its respective ends to the top rails of the end frames, preferably by providing tunnels 16 at the ends of the canvas through which the rods extend. The studs 10 which are engaged by braces 8 project through suitable openings in the canvas, and the medial portions of the tunnels 16 are preferably cut away as shown at 17 so as to expose rails 4 and permit tensioning straps 18 being looped over the same. The opposite ends of the straps are received through eyes 19 mounted on members 1 beyond the end frames of the cot, so that tightening of the straps by means of buckles 20, will swing the end frames upon the axes of rails 5 and thereby shift rails 4 away from one another to tension the canvas.

In folding the cot, buckles 20 are released so that straps 18 may be removed from top rails 4, and braces 8 are disengaged from rails 4 so that the end frames of the cot may be collapsed as shown in Fig. 3. The

hinged members 1 forming the base bar are then folded on one another and at the same time the collapsed end frames are turned parallel to members 1 so that the canvas 15 connected at its ends to the top rails of the end frames will form a flat loop projecting laterally from the folded frame. The canvas may then be wrapped around the folded frame as shown in Fig. 4.

10 I have thus provided a cot which may be folded into a compact form, and which when extended for use provides a rigid construction without the use of side rails. The end frames are held rigid by the braces 8, and said end frames may be swung so as to longitudinally stretch the canvas 15 to any desired degree by tightening the straps 18. The members 1 of the base bar being held against folding by the abutment of their ends 3, the cot is thus longitudinally braced and held rigid by the straps; and at the same time the structure is braced against transverse strain by the rigidity of the end frames and the abutment thereof against the ground at points spaced transversely beyond opposite sides of the base bar.

I claim:

1. In a folding cot, a base bar comprising sections adapted to fold upon one another or extend beyond one another in longitudinal alinement, end frames comprising top and bottom rails and uprights connecting the same, means for forming rigid structures of said end frames with the top rails spaced above the bottom rails or collapsing said end frames with the top rails in juxtaposition with the bottom rails, means for mounting the bottom rails of the end frames on the respective sections of the base bar so that the end frames extend transversely of the base bar with the top rails of the end frames adapted for vertical swinging movement away from one another longitudinally of the base bar, a flexible body support connected at its respective ends to the top rails of the end frames, and adjustable connections between said top rails and the respective sections of the base bar beyond said end frames for swinging said top rails so as to tension the body support.

2. In a folding cot, a base bar comprising sections adapted to fold upon one another or extend beyond one another in longitudinal alinement, end frames comprising top and bottom rails and uprights connecting the same, means for forming rigid structures of said end frames with the top rails spaced above the bottom rails or collapsing said end frames with the top rails in juxtaposition with the bottom rails, means for mounting the bottom rails of the end frames on the respective sections of the base bar so that the end frames when collapsed will extend along the sections of the base bar and when rigid structures are formed of the end

frames the latter will extend transversely of the base bar with the top rails of the end frames adapted for vertical swinging movement away from one another longitudinally of the base bar, a flexible body support connected at its respective ends to the top rails of the end frames, and connections between said top rails and the respective sections of the base bar beyond said end frames for swinging said top rails so as to tension the body support.

3. In a folding cot, a base bar, end frames comprising top and bottom rails and uprights connecting same, means for forming rigid structures of said end frames with the top rails spaced above the bottom rails or collapsing said end frames with the top rails in juxtaposition with the bottom rails, means for mounting the bottom rails on the base bar so that the end frames when collapsed will extend along the base bar and when rigid structures are formed of the end frames they will extend transversely of the base bar with the top rails of the end frames adapted for vertical swinging movement away from one another longitudinally of the base bar, a flexible body support connected at its respective ends to the top rails of the end frames, and means for swinging the end frames away from one another so as to tension the body support between the top rails.

4. In a folding cot, a folding base, end frames connected to the base so as to prevent detachment therefrom, a flexible body support, and means for tensioning the body support between the end frames, and means for collapsing the end frames on the folded base longitudinally thereof with the body support wrapped around the collapsed end frames and folded base.

5. In a folding cot, a base, end frames connected to the base so as to prevent detachment therefrom, a flexible body support, means for tensioning the body support between the end frames, and means for folding the base and end frames into longitudinal juxtaposition with the body support wrapped around the same.

6. In a folding cot, a base bar, end frames comprising top and bottom rails, uprights connecting the same, means for forming rigid structures of said end frames with the top rails spaced above the bottom rails or collapsing said end frames with the top rails in juxtaposition with the bottom rails, means for mounting the bottom rails of the end frames on the base bar so that the end frames extend transversely of the base bar with the top rails of the end frames adapted for vertical swinging movement away from one another longitudinally of the base bar and a flexible body support connected at its respective ends to the top rails of the end frames and tensioned by said swinging of the top rails.

7. In a folding cot, a base bar, end frames adapted to form rigid structures extending transversely of the base bar or collapsed structures extending along the base bar, the 5 end frames when forming rigid structures being adapted for swinging of the upper ends thereof away from one another longitudinally of the base bar, and a flexible body support connected at its respective ends to 10 the swinging upper ends of the end frames for tensioning said body support between the end frames.

8. In a folding cot, a base bar, end frames adapted to form rigid structures extending 15 transversely of the base bar or collapsed structures extending along the base bar, the

end frames when forming rigid structures being adapted for swinging of the upper ends thereof away from one another longitudinally of the base bar, a flexible body support connected at its respective ends to the swinging upper ends of the end frames, and connections for swinging the upper ends of the end frames to tension the body support, said connections being separable to 20 permit collapse of the end frames on the base bar with the body support wrapped around the collapsed end frames and base. 25

In testimony whereof I have affixed my signature to this specification.

WILLIAM E. BROWN.
